LUBRICATING DEVICE

Le Roy White, Shillington, Pa., assignor to
 Textile Machine Works, Wyomissing, Pa., a corporation of Pennsylvania

Application December 24, 1943, Serial No. 515,621

1 Claim. (Cl. 184—14)

1

The present invention relates to the lubrication of revolving wear surfaces such as those of cam mechanisms and more particularly to the lubrication of couliering cams such as are used in full-fashioned knitting machines.

The wear surfaces of certain cams and their followers are subject to high unit pressures and require frequent application of lubricant in use but nevertheless operate under conditions making it impractical or undesirable to utilize the immersion or splash oiling method which requires a large quantity of oil. Such a cam means is the couliering cam and followers of a full-fashioned knitting machine, the proper lubrication of which has been difficult, resulting in an undesirably high rate of wear or waste of oil with resulting untidiness and fire hazards.

It is an object of the invention to provide an arrangement adapted to oil the wear surfaces of cams working under high maximum unit pressures and which will reliably supply sufficient quantities of oil to the contacting surfaces of the cam and follower means to minimize the rate of wear.

Another object of the invention is to provide an oiling means for a coulier or like cam which will be simple in construction and operation, and which will be of low cost to manufacture.

Still another object is to provide means for oiling a cam and adapted to supply an ample amount of oil to the cam from a comparatively small pool of oil.

A still further object of the invention is to provide a method of oiling wear surfaces which will be reliable and may be carried out with compact and simple means as well as with a small pool of oil.

With these and other objects in view, which will become apparent from the following detailed description of the illustrative embodiment of the invention shown in the accompanying drawings, my invention resides in the novel device comprising the new elements, features of construction and arrangement of parts in cooperative relationship as hereinafter more particularly pointed out in the claim.

In the drawings:

Figure 1 is a rear elevation of a portion of a full-fashioned knitting machine showing certain of the operating parts thereof and the oiling means of the invention in position to cooperate therewith;

Fig. 2 is a detail view of a portion of Fig. 1 on an enlarged scale compared to Fig. 1 showing the

2

coulier cam in elevation and certain adjacent parts in section;

Fig. 3 is a view similar to Fig. 2 but showing the coulier cam in a different position;

Fig. 4 is a detail plan view of the oiling means shown in Figs. 1, 2 and 3, taken on the line 4—4 of Fig. 1; and

Fig. 5 is a detail sectional view taken on the line 5—5 of Fig. 1.

10 An oiling means within the present invention adapted to carry out the foregoing objects comprises a means which is in contact at least at times with the wear surface of a cam and is actuated thereby to transfer oil from a pool thereof to the surface of the cam. Preferably, the means which brings up oil to the cam is moved by the cam to alternately dip below the surface of the oil and to transfer oil upwardly to the surface of the cam. If desired, the part or member 20 for elevating oil to the cam may have a flat or plate-like surface for contacting the surface to be oiled, but the invention is not limited to this in all cases.

In the arrangement shown in the drawings, 25 10 designates each of certain transverse frame members which are connected by longitudinal frame members such as the back-beam 12 and the center bed 14 to form a rigid framework for the operating parts of a full-fashioned knitting machine which is assumed to be of a known construction. The operating parts of the machine shown include the coulier shaft 16 at the rear end of which is fixed a coulier cam 18 eccentrically mounted on and revolving with the shaft and contacting at two horizontally opposite points 30 two rotatable followers 20, 20, Fig. 1, which are mounted to revolve on a horizontal link 22, so that link 22 is reciprocated in use by cam 18. At its opposite ends, link 22 is pivoted to two levers 24 and 26 respectively which are mounted to oscillate in unison with each other in synchronism with cam 18 and link 22. The pivot for lever 24 is at its lower end in a bracket 28 suspended from back-beam 12 while the upper end of lever 24 is at 35 pivoted to a link 30, link 30 being pivoted in turn to a cross head 32 which is reciprocated by the link and lever. Cross head 32 is mounted for reciprocation on a guide bar 34 fixed to the center bed 14 and is connected at its upper end to a 40 reciprocating friction box rod 36 which in use drives the friction box or friction boxes for connection to the yarn carrier rods and yarn carriers by which yarn to be knitted is supplied to the needles.

45 The pivot for the lever 26 is shown supported

on a bracket arrangement 38 at the upper end of lever 26, arrangement 38 being fixed to the center bed 14 and back beam 12. Near its mid-point, lever 26 is pivoted to one end of a link 40, the other end of which is pivoted to a lever 42, lever 42 being pivoted at its lower end in a bracket arrangement 44 fixed to the back-beam 12. Lever 42 is connected at its upper end to a half-speed friction box rod (not shown) the uses of which are well understood and which will not be further described.

It will be understood that the mechanism hereinabove described is in itself all well known and, except as it combines or cooperates with the oiling means according to the invention, forms no part of the present invention.

In the operation of the coulier mechanism as above described, the rotation of cam 18 reciprocates link 22 and thereby reciprocates through levers 24, 26 and 42 the friction box rod 36 and the half-speed rod and the parts connected thereto. As the reciprocating parts accelerate, the pressure of the contacting surfaces of cam 18 and followers 20 is high and this is especially so as the parts stop moving in one direction and start to move in the opposite direction.

Adequate amounts of lubricant must therefore be regularly supplied to the active surface of cam 18 or the active surfaces of followers 20, or both, in order to prevent excessive wear of these parts. Owing to the precise register desired between the yarn carriers on the one hand and the sinkers, dividers and needles on the other, very little lost motion is permissible between the cam and the followers and therefore the rate of wear must be held to the minimum.

For supplying the required lubricant for cam 18, a pan 46 is commonly provided which is suitably fixed to the framework of the machine as by screws 48 passing through lugs 50 into the back beam 12, pan 46 being shown as of a usual form and as having a shallow pool of oil 52 therein, Figs. 2, 3 and 5. Owing to the swinging movements of the link 22 and followers 20, it is difficult to enclose the cam 18 and followers 20 sufficiently to prevent them from throwing out oil and thereby creating a nuisance in the form of waste oil which may cause accidents from falling, which mixes with and holds dirt and causes a fire hazard. The pool 52, in accordance with the present invention, is kept at a shallow level so that the cam 18 does not strike it during the revolution of the cam, thus, the objectionable throwing and/or splashing of oil is avoided.

In order to lubricate the cam 18, a novel arrangement is provided whereby oil is elevated from the pool 52 and applied to the wear surface of the cam 18. To this end, there is shown a member preferably in the form of a flexible strip or narrow plate 54 so formed and supported that it is biased to a position above the oil level but which is pressed down at times by the cam 18 so as to dip into the oil and raise some oil into contact with the cam, this occurring in the arrangement shown once in each revolution of the cam. As shown, the strip 54 extends generally lengthwise of the pan 46 and parallel to the beam 12 in the plane of the cam 18. At one end, the strip 54 is shown as fixed by screws or rivets 56, Fig. 4, to a supporting bracket 58 at a point near the level of oil pool 52. As shown, the strip 54 extends from its connection with bracket 58 in a general lateral plane above the pool of oil but below the cam 18. In the illustrated embodiment of the invention, the strip 54 is bent upwardly,

to provide a length inclined to the horizontal when strip 54 is free from pressure. At about the vertical line through the shaft 16, strip 54 is bent again, thereby providing an upper bend or angle 55 in the plane of operation of certain portions of the cam 18 and a length 59 which lies substantially horizontal when strip 54 is free from pressure. The oiling strip is shown as tapering to a rounded point 60 at its free end. The supporting bracket 58 is shown as extending transversely of the oil pan 46 from its point of connection with strip 54 at about the oil level to the rear side of the oil pan and then up to about the upper edge of the pan where it is shown as fastened to the pan by a screw 66, Fig. 5. It will be understood that the invention is not limited to a particular form or method of supporting the strip 54.

A certain degree of resiliency is essential to the operation of the particular form of the invention shown in order that the strip 54 may lift itself from the oil pool after being pressed at least partially below its surface. As shown, the horizontal portion 59 of strip 54 is resilient enough and of such shape to maintain contact with the surface of the cam 18 throughout substantially the length of said portion 59, that is, from the upper bend 55 in the strip to its outer free end 60. By such construction a material amount of oil is elevated to the cam surface, and in such manner as to regularly lubricate the cam from a suspended oil supply without splashing.

In operation, when cam 18 revolves it lies entirely above and out of contact with strip 54 during the greater part of each revolution. The strip is therefore free to stand, as shown in Figs. 1, 3 and 5, in a position in which the portion thereof adapted to contact cam 18 lies above the oil level and intermediate cam 18 and the oil pool 52. As the cam 18 rotates certain portion or portions on its surface as it approaches the lower level, i. e., the vertical line through the axis of shaft 16, brings the cam into contact with the strip 54 at the point of its upper bend or an angle 55. As viewed in Fig. 3, as the cam revolves after its initial contact with the strip, its lowest spot moves downward between the moment of initial contact and the moment at which the parts are in the positions shown in Fig. 2, the cam pressing strip 54 farther and farther downward and into the oil of pool 52 in the period between said two moments, bend 55 naturally revolving about bracket 58 as an axis and therefore swinging somewhat to the left as viewed in Fig. 3 as it moves downward. The lowest position of strip 54 is as shown when the said lowest spot on the surface of cam 18 is the one in the vertical line through the axis of shaft 16, this being the position of the parts shown in Fig. 2 in which the point of maximum radius of the cam is directly beneath its axis and the free end of strip 54 is some distance beneath the surface of pool 52. As the cam 18 then begins to rotate from the position shown in Fig. 2 toward that shown in Fig. 3, the point of contact between cam 18 and strip 54 moves still farther toward the left as viewed in Fig. 2 until it reaches the end or tip 60, so that the oil on the upper surface of strip 54 is wiped off onto the cam over a sufficient length of the perimeter of the cam to transfer the required amount of oil to the cam surface. The oil is then spread during the operation of cam 18 and followers 20 so that a film of the necessary thickness is maintained over the entire working surface of the cam. Moreover, the alternate dipping and elevating of the end 60 will cause a continuous deposit of oil upon the whole

surface of the substantially horizontal length 59, whereby to increase the effective oil transfer area of the strip 54.

While the invention is not limited as to the point of support of the strip 54, it is preferred that if the point of the cam at maximum distance from the axis of rotation moves from, say, right to left when the cam is viewed from a certain direction the part 54 be supported at the right of the axis of rotation as viewed from said direction. This arrangement is the one shown and gives a smooth wiping action between cam 18 and strip 54. The strip 54 as shown is of thin resilient metal, stamped from a sheet and pressed into the shape shown. However, the invention is not limited to the use of metal or to thin material. Further, the arrangement shown requires very little space and can be mounted entirely within the usual oil pan while the oil level in the pan can be relatively low so that only a small amount of oil need be in use at any one time, leading to economy in the use of oil.

As appears clearly in Fig. 4, the free end of strip 54 tapers from a point near its upper bend in the strip nearly to a point at the end and while the wider portions of the strip are not as wide as the face of cam 18 as appears in Fig. 5. While the invention is not limited to strips having the proportions shown, such a strip, relatively to a coulier cam, has been found to supply the desired amount of oil to the cam and without splashing or otherwise wasting oil.

The method according to the invention of lubricating the wear surfaces of cams and the like will be obvious to those skilled in the art from the foregoing descriptive matter.

Of course, the novel device shown and described and the novel method by which I obtain the referred to advantageous results, can be changed

and modified in various ways without departing from the invention herein disclosed and herein-after claimed.

I claim:

- 5 The combination with a coulier cam of a flat knitting machine mounted to revolve above and out of contact with the surface of an oil pool in a container, of lubricating means for said cam comprising a resilient strip mounted below and generally in the plane of said cam, said strip supported at one end, biased toward a position generally above the oil, and having a bend therein intermediate its ends and tapering from said bend toward its free end, said bend cooperating with said cam during a portion of its revolution to force said free end beneath the oil, the strip when in normal raised position having a wiping contact with a portion of the surface of the cam to transfer oil thereto, and the width of the tapered portion of said strip being proportioned relatively to the throw and width of the cam so as to supply sufficient oil to the cam.

LE ROY WHITE.
